UNITED STATES PATENT OFFICE.

ALBERT KLFKE, OF MUNICH, GERMANY.

LOCK FOR NUTS AND SCREW HEADS.

Application filed November 18, 1926, Serial No. 149,117, and in Germany October 14, 1926.

This invention relates to a lock for nuts and screw heads. The invention consists essentially in utilizing for locking the nut or the screw head a washer having an upwardly turned inner edge or upwardly turned extensions on the inner edge designed to engage with an outwardly inclined groove of the nut to lock the same. The upwardly turned edge or the upwardly turned projections of the washer are tightly upset in the groove or cavity of the nut when the nut is being screwed tight, whereby a secure connection between nut and washer is created. The washer is secured against rotation, by any convenient means, the nut rigidly connected to the washer being at the same time locked against accidental rotation.

Several embodiments of the invention are shown, by way of example, on the accompanying drawing in which:—

Fig. 1 shows in longitudinal section a nut according to the invention,

Fig. 2 shows in section and

Fig. 3 in top plan view the corresponding washer.

Fig. 4 shows in longitudinal section the nut and the washer in the locked position on a screw bolt which is shown in elevation.

Fig. 5 shows in longitudinal section a washer of modified construction.

Fig. 6 shows in longitudinal section a nut of modified construction.

Fig. 7 shows in side elevation and

Fig. 8 in top plan view a third form of construction of the washer.

Figs. 9 and 10 show in longitudinal section the upwardly turned projections of the washer shown in Figs. 7 and 8.

Fig. 11 shows in longitudinal section and Fig. 12 in top plan view a further form of construction of the nut.

Fig. 13 shows in top plan view the improved nut lock used on railway sleepers in combination with a helical spring.

Fig. 14 is a cross section of Fig. 13.

Fig. 15 shows in section, partly in elevation, the washer with spring prior to the tightening of the nut.

Fig. 16 shows in a section on line 16—16 of Fig. 13 the washer after the tightening of the nut.

Fig. 17 shows in side elevation and

Fig. 18 in top plan view a modified construction of the washer shown in Figs. 13 to 16.

Referring to the drawings *a* is the nut and *b* the washer. The washer has an upwardly turned inner edge *c* fitting into a cavity *d* of the nut *a*. The cavity *d* is produced for instance by backing off of the nut which nut 60 may have at this part a thinner wall. The cavity *d* might however be produced by slitting the wall of the nut.

The upwardly turned inner edge *c*, or collar of the washer *b* is slit or subdivided 65 into stud-like portions which are higher than the cavity *d* in the nut is deep. The conical portion *f* of the circular thread of nut *a* comes into contact with the inner edge of the collar *c* of the washer when the nut is 70 being screwed on. When the nut is being tightened the collar *c* or the stud like portions of the same are pressed in outward direction so that the collar slips behind the conical portion *g* of the nut *a* formed by the 75 cavity *d*. As the collar *c* is higher than the cavity *d* of nut *a* is deep, the collar *c* or the stud like parts of the same are upset when the nut is tightened so that its lower surface rests upon the top surface of the washer *b*,

so that the collar or the stud like parts of the same are strongly compressed between the walls of the conical portion of the cavity *d* and securely connected with the nut 80 (Fig. 4). The secure connection between 85 washer and nut may be further increased by roughening or fluting the stud like parts of collar *c* or the cavity *d* of the nut on the inner and outer walls or on the inner or on the outer wall. By the pressure exerted by 90 the upset parts of collar *c* the threads of nut *a* are tightly pressed into the threads of the screw bolt *h* (Fig. 4).

The subdivided collar *c* of the washer *b* may be bevelled on the outer side. Fig. 5 95 shows, for instance a washer the stud like parts of the collar *c* of which are alternately bevelled on the top edge of the outer and inner surface. The studs or parts of the collar *c* which are bevelled on the inner side 100 may be longer than those bevelled on the outer side. When washers are shown in Fig. 5 are used the studs or parts of the collar *c* which are bevelled on the inner side are pressed into the cavity *d* of the nut when said nut is tightened, whilst the studs or parts of the collar *c* which are bevelled on the outer side are pressed inward into the threads of screw *h* (Fig. 4). In connection 105 with a washer as shown in Fig. 5 a nut as 110

shown in Fig. 6 is preferably used which comprises, besides the conical surfaces *f*, *g* of the cavity *d*, a conical surface *s* which is inwardly directed towards the thread and with which the studs or parts of collar *c* come into engagement which are bevelled on the outer side so that they are pressed inwardly into the thread of the screw bolt *h*.

As shown in Fig. 7 to 10 the studs or parts 10 of the collar *c* may be of different thickness. The studs *c'* designed to be pressed inwardly into the thread of the screw bolt are thinner than the studs *c''* designed to be pressed outwards into engagement with the cavity *d* 15 of the nut. The bevelings at the edges may be of any shape, the thin studs *c'* might, for instance, be conical over their entire length and be more or less sharply pointed.

The nut *a* might have cut out portions *e* 20 (Figs. 11 and 12) in the surface of which the cavity and the backed off cone *g* are arranged. When the nut is being screwed on, the studs *c* are upset by the action of the conical walls of cavity *d*. Owing to the 25 cut out portions *e* at least one stud *c*, instead of being upset, will be pressed outwards into engagement with the cut out portion *e*. When the cut out portions *e* are unsymmetrically arranged with regard to the symmetrical 30 arrangement of the studs *c* of the washer *b* one of the studs *c* will engage with one of the cut out portions *e* of the nut after a slight rotation of the nut *a* so that this nut is automatically locked by this stud of the 35 washer. In this form of construction all the studs *c* may be bevelled on the inner side.

When the cut out portions *e* of the nut are displaced with regard to the symmetrical 40 arrangement of the studs or parts of collar *c* of the washer *b* they might form together with the gap between two studs *c* continuous openings into which, for instance, a cotter, split pin or the like might be inserted.

The washer *b* may be of various constructions 45 in order to prevent turning of the washer. With this object in view the washer *b* might be flat on one side (Fig. 3) or it might be roughened, fluted or have pyramid-shaped, cone shaped or pointed projections 50 *i* (Fig. 5) on one side. At certain points of the washer flaps might be stamped out of the washer so that they project towards the support for the washer (Figs. 7 and 8). The resilient flaps *t* exert a locking action against 55 accidental backward rotation of the nut or of the washer.

The invention might be used in connection 60 with the spring washers for the screw connection of railway rails or sleepers, as shown in Figs. 14 to 16. In these figures of the drawing *b* is the washer which has the inner edge *c* turned up, said edge being eventually subdivided into several stud-like parts. The washer *b* has at the outer edge downwardly 65 bent flaps *r* and it is designed to accommodate

a helical spring *a* (Fig. 15). The outer edge of the washer has cut out portions *v* so that the flat portion of the washer, the inner edge of which forms the vertical collar *c*, can bend downwards at the tightening of the 70 nut and put the spring *u* under tension (Fig. 16). With this object in view the flat portion of the washer which carries the upwardly turned collar *c* is elastic, *z* is the part of the rail and sleeper connection in which 75 the washer, nut and spring *u* are located.

The washer *b* may be reinforced by ribs *y* (Figs. 17 and 18) extending from the flat portion over the bent outer edge and the downwardly directed flap *r*. These flaps *r* 80 may grip over projecting portions of the rail and sleeper connection and they might be provided on one side only.

The described lock device can also be used 85 in combination with the head of screw bolts, in which case the head of the bolt instead of the screw-nut is provided with the described cavity *d*.

I claim:—

1. A lock for nuts and screw heads, comprising in combination, a nut having a cavity 90 in the lower surface, and a washer, an upwardly turned collar on the inner edge of said washer subdivided into several separated stud like parts designed to independently engage with and be bent by said cavity of said nut to lock said nut in its position.

2. A lock for nuts and screw heads, comprising in combination, a nut having a cavity 100 in the lower surface, and a washer, an upwardly turned collar on the inner edge of said washer subdivided into several separated stud like parts bevelled on one side of the top edges and designed to independently engage with and be bent by said cavity of 105 said nut to lock said nut in its position.

3. A lock for nuts and screw heads, comprising in combination, a nut having a cavity 110 in the lower surface, and a washer, an upwardly turned collar on the inner edge of said washer subdivided into several stud like parts alternately bevelled on the one side and on the other side of said edges and designed to engage with said cavity of said nut so that said stud like parts are bent inward or outward by the tightened nut to lock 115 said nut in its position.

4. A lock for nuts and screw heads, comprising in combination, a nut having a cavity 120 in the lower surface, and a washer, an upwardly turned collar on the inner edge of said washer subdivided into several stud like parts of different thickness and designed to engage with said cavity of said nut to lock said nut in its position.

5. A lock for nuts and screw heads, comprising in combination, a nut having a cavity 125 in the lower surface, and a washer, an upwardly turned collar on the inner edge of said washer subdivided into several stud 130

like parts of different length and designed to engage with said cavity of said nut to lock said nut in its position.

6. A lock for nuts and screw heads, comprising in combination, a nut having a cavity in the lower surface formed by a backed off slot and having cut out portions, and a washer, an upwardly turned collar on the inner edge of said washer subdivided into several stud like parts and designed to engage with said cavity of said nut, some of said stud like parts designed to engage with some of said cut out portions of said nut, to lock said nut in its position.

15 7. A lock for nuts and screw heads, comprising in combination, a nut having a cavity in the lower surface, and a washer, an upwardly turned collar on the inner edge of said washer subdivided into several stud like parts alternately bevelled on the one side and on the other side of said edges and designed to engage with said cavity of said nut, and a cone in said nut turned towards the thread, so that some of said stud like parts are bent inward by the tightened nut to engage with the threads of the screw bolt, to lock said nut in its position.

8. A lock for nuts and screw heads, comprising in combination, a nut having a cavity in the lower surface, and a washer, an upwardly turned collar on the inner edge of said washer and designed to engage with

said cavity of said nut and to be upset when said nut is being turned to lock said nut in its position, and a helical spring underneath 35 said washer.

9. A lock for nuts and screw heads, comprising in combination, a nut having a cavity in the lower surface, and a washer, an upwardly turned collar on the inner edge of 40 said washer, and designed to engage with said cavity of said nut and to be upset when said nut is being turned to lock said nut in its position, a downwardly turned flange at the outer edge of said washer, and a helical 45 spring underneath and inside the downwardly turned flange of said washer.

10. A lock for nuts and screw heads, comprising in combination, a nut having a cavity in the lower surface, and a washer, an 50 upwardly turned collar on the inner edge of said washer and designed to engage with said cavity of said nut and to be upset when said nut is being turned to lock said nut in its position, a downwardly turned flange 55 at the outer edge of said washer, the flat portion of said washer having stamped out downwardly directed flaps so that it is elastic, and a helical spring underneath and inside the downwardly turned flange of said 60 washer.

In testimony whereof I affix my signature.

ALBERT KLAFKE.
